UNITED STATES PATENT OFFICE

2,504,043

BUILDING FORM

Joseph Parker, Oakland, Calif.

Application August 31, 1946, Serial No. 694,252

3 Claims. (Cl. 25—131)

1

My invention relates to improvements in forms for building houses of concrete, or cement.

The primary object of the invention is to provide a form of few parts and simple construction for building hollow-walled houses with concrete, or cement, laid in courses, and which is adapted to be filled, knocked down and set up for refilling to build the courses progressively in hollow sections, all to the end of reducing the cost of concrete houses while achieving, without the use of laid concrete blocks, strong walls with an unbroken heat and cold air insulating space therein extending throughout the entire wall and maintaining the same dry.

Other and subordinate objects, also comprehended by my invention, together with the precise nature of my improvements, and the advantages thereof, will be readily understood when the succeeding description and claims are read with reference to the drawings accompanying and forming part of this specification.

In said drawings:

Figure 1 is a view in plan illustrating my invention in a preferred practice thereof, and the manner in which the same is used in constructing a hollow walled building.

Figure 2 is a view in vertical section drawn to a larger scale and illustrating the manner in which the form is set up and partly filled and tamped in building a section of a course of the wall.

Figure 3 is a similar view with the yokes of the core removed and the form further filled and tamped.

Figure 4 is a view in perspective of the form set up with the yokes of the core removed.

Figure 5 is a view in perspective of the core set up.

Figure 6 is a view in perspective illustrating the corner form and panels of a pair of forms to which the corner form may be attached.

Figure 7 is a view in perspective of the panels of the core with the spacing bars swung out of spacing position.

Referring to the drawings by numerals, and more particularly to Figures 4, 5, and 6, the form of my invention, designated as a unit by the numeral 1, comprises a pair of elongated rectangular, side panels 2 of wood, preferably, with a thin metal lining 3 suitably fixed thereto, and detachably secured together in laterally spaced, parallel relation, with linings 3 facing, the spacing between the panels 2 corresponding to the thickness of the walls to be built.

The panels 2 are designed to be used to form

2

the outer sides of a hollow wall and to be applied in upright position with longitudinal edges uppermost and lowermost respectively.

For securing the panels 2 together a pair of knock down yokes 4 are provided adjacent the ends of said panels 2 and which straddle the pair of panels and extend above the same.

The yokes 4 each comprise a pair of uprights 5, preferably of wood, fixed in any suitable manner, not shown, to the outer sides of the panels.

2. Each pair of uprights 5 is detachably connected together, immediately above the upper edges of the panels 2, by a pair of cross tie bars 6 opposed to opposite sides of the pair of uprights with ends bolted, by pivot bolts 7, to said uprights. The pivot bolts 7 provide for swinging adjustment of the pairs of uprights 5, laterally in each pair, to correspondingly adjust the pair of panels 2 into exact parallel relation in setting up the form.

A pair of cross tie bars 8 detachably connect the upper ends of the uprights 5 of each pair, upon opposite sides of the uprights, and are bolted at one end by a pivot bolt 9 to one upright 5, with the other ends thereof bolted, by a pivot bolt 10, to the other upright of the pair; the bolts 10 extending through longitudinal slots, as at 11, in the cross tie bars 8 and being equipped with wing nuts 12 thereon. As will be seen, the slots 11 and wing nuts 12 provide for locking the pairs of uprights in different adjusted positions to maintain the panels parallel.

A pair of diagonal brace bars 13 detachably connect the uprights 5 of each pair, between the tie bars 6 and 8, and are secured to opposite sides of the pair of uprights 5 by a pivot bolt 14, at one end of the bars, and a pivot bolt 15 at the other ends of said bars extending through longitudinal slots 16 in the bars 13 and equipped with a wing nut 17. The diagonal brace bars 13, as will be seen, brace the pairs of upright 5 in different adjusted positions of said uprights.

A block 18 is fitted in between each pair of cross tie bars 6 and bolted thereto, as at 18, in the transverse center of the pair. The blocks 18 are provided with lower, corner notches 19 below the cross tie bars 6 and function as centering members for a core presently described.

By removing the pivot bolts 7, 9, 10, 14, 15, the described bars 6, 8 and 13 may be detached from the yokes 4 and said yokes knocked down to disassemble the same and the panels 2.

A pair of hinge eyes 20 are provided on one end of one of the panels 2 for a purpose to be explained.

In addition to the foregoing, the form 1 includes a core, now to be described. The core comprises a pair of side panels 22, preferably of wood, adapted to be arranged in laterally spaced, parallel relation between the panels 2 and centered therebetween with the panels 22 spaced apart a distance corresponding to the space desired in a hollow wall. The panels 22 may be substantially of the same length as the panels 2 and are provided with a metal facing 23, respectively, on the outer sides and along the longitudinal edges thereof, corresponding to the linings 3.

A pair of spacing cross bars 24 are hinged to one panel 22, as at 25, adjacent the ends thereof, to be swung into and from spacing positions to separate the panels 22 the desired distance apart in setting up the core.

A pair of yokes 26, similar to the yokes 4, with pairs of uprights 27, are providing for straddling panels 22 adjacent opposite ends thereof to hold the panels 22 against spreading apart from spaced relation, said yokes 27 being removable for a purpose to be seen.

A pair of upper and lower cross bars 28, 29, in each pair connect each pair of uprights 27 above the panels 22, the lower cross bar 29, in each pair, being secured to the uprights 27 by pivot bolts 30, whereas, the upper cross bars 28 are secured to said uprights by pivot bolts 31 extending through slots 32 in said bars 27 and equipped with wing nuts 33. The pivot bolts 30, 31 and the slots 32 and the wing nuts 33 provide for swinging adjustment of the pairs of uprights 27 to clamp the same against panels 22 flush therewith in setting up the core, and by loosening the wing nuts 33, said pairs of uprights 27 may be swung on the pivot bolts 30 away from said panels 22 for ready removal of yokes 27 so that the core 21 may be knocked down at will.

Spacing strips 34 are provided for insertion between said panels 2 and 22, temporarily, until the mold 1 is partly filled with concrete and anchored thereby after which said strips may be removed.

A corner form 35 is provided comprising a pair of like, substantially square panels 36 having beveled edges 37 hinged together, as at 38, for folding of said panels into right angular, set relation, the edges of said panels 36, opposite the hinged edges 37, being provided with pairs of hinge eyes 39 for attachment to the hinge eyes 20 on panels 2 of a pair of the forms 1. Pins, as at 40, provide for such attachments.

As best shown in Figure 4, in setting up the described form 1, the core is centered in between the panels 2 by inserting the upper longitudinal edges of panels 22 in the notches 19 of the blocks 18.

In using the described form 1, the wall is built up in courses 41, 42, 43, for instance, as shown in Figures 2 and 3, with cross tie rods 44 between said courses, and the form is set up with the panels 22 of the core resting upon said tie rods 44, as shown in Figures 2 and 3, and then partly filled and tamped with a wet mix of concrete, as shown in Figure 2, after which the yokes 26 are removed from form 1 as shown in Figures 3, 4. The form 1 is then filled, substantially and tamped to build up a section of a course, for instance course 43 as shown in Figure 3, and then knocked down and again set up and shoved forward on said section for building up another section of the course. The tie rods 44 are left in the wall and longitudinal tie rods 45 may be used in the courses. In building corners and as shown

in Figure 1, a pair of forms 1 are used, in right angular relation, to build corners in the courses, and with the panels 2 of the forms 1 on the inside of the corners arranged in butt joint relation, and the panels 2 of said forms, on the outside of the corners, connected by the corner form 35, the hinge eyes 39 of which are secured by the pins 40 to the hinge eyes 20 on one panel 2 of each form 1. The panels 22 of the cores 1, of the 10 thus connected forms are shifted longitudinally into butt joint relation, as at 46, 47. As also shown in Figure 1, a window frame 48 may be interposed between the panels 2 of a form 1 so that the wall may be built up to said frame, and 15 screws 49 may be driven into the frame 48, diagonally, and embedded in the wall to tie said frame and wall together. The numeral 50 designates a brick window sill which needs merely be identified in passing.

In filling the form 1, of my invention, to build a hollow wall in accordance with the method described, a concrete mix is to be used which is of a consistency such that the mix will not run out of the open ends of the form as would happen 25 with the usual poured mix.

The foregoing will, it is believed, suffice to impart a clear understanding of my invention, without further explanation.

Manifestly, the invention, as described, is susceptible to modification without departing from the inventive concept, and right is herein reserved to such modifications as fall within the scope of the appended claims.

What I claim is:

35 1. A form for molding hollow concrete walls comprising a pair of elongated rectangular panels, a pair of knock down yokes straddling the pair of panels adjacent opposite ends thereof and spacing the same apart laterally, a core interposed between the pair of panels comprising a second pair of elongated rectangular panels, means interposed between said second pair of panels and spacing the same apart laterally, and means on said yokes interposed between the second pair of panels to center the core between the pair of panels first mentioned, the first mentioned means comprising bars hinged to one panel of the second mentioned pair for swinging into crosswise position relative thereto into effective spacing position, and yokes straddling said second pair of panels with pivoted uprights swingable to clamp said second pair of panels to opposite sides of said bars.

55 2. A form for molding hollow concrete walls comprising a pair of elongated rectangular opposed panels, a core interposed between said pair of panels including a second pair of elongated rectangular opposed panels, means confining the first mentioned pair of panels against relative separation and including devices for centering the core between the first mentioned pair of panels, and means for spacing the second mentioned pair of panels apart comprising bars hinged to one panel of the second mentioned pair for swinging into crosswise position relative to the pair into effective spacing position, and yokes straddling said second pair of panels with pivoted uprights swingable to clamp said second pair of panels to opposite sides of said bars.

60 3. In a form for molding hollow concrete walls, a core including a pair of opposed panels, and means for spacing said panels apart comprising bars hinged to one panel of the pair for swinging into crosswise position relative to the pair into effective spacing position, and yokes straddling

said pair of panels with pivoted uprights swingable to clamp the panels of said pair to opposite sides of said bars.

JOSEPH PARKER.
